UNITED STATES PATENT OFFICE.

RAYMOND C. KNOPKE, OF WHEATON, ILLINOIS, ASSIGNOR, BY MESNE ASSIGNMENTS, TO INLAND STEEL COMPANY, OF CHICAGO, ILLINOIS, A CORPORATION OF DELAWARE.

FENCEPOST.

Application filed November 18, 1922. Serial No. 601,711.

To all whom it may concern:

Be it known that I, RAYMOND C. KNOPKE, a citizen of the United States, residing at Wheaton, in the county of Du Page and State of Illinois, have invented new and useful Improvements in Fenceposts, of which the following is a specification.

This invention relates to metal fence posts and has particular reference to the manner 10 of securing anchor plates thereto.

The main object of my invention is to provide fastening means which will enable anchor plates to be secured to the posts without requiring that holes be made in the latter to weaken them as heretofore.

The invention consists further in the matters hereinafter described and more particularly set forth in the appended claim.

In the accompanying drawings—

20 Fig. 1 is a front view of a metal fence post having an anchor plate secured thereto in accordance with my invention;

Fig. 2 is an enlarged transverse sectional view taken on line 2—2 of Fig. 1;

25 Fig. 3 is a longitudinal sectional view taken on line 3—3 of Fig. 2; and

Fig. 4 is a front view of the anchor plate without the fastening member.

In the drawings, I have shown a metal 30 fence post having a flat back 1 extending the full length of the post and provided with a pointed lower end 2 to facilitate driving the post into the ground. Integral with the back 1 on the rear side thereof is a web or flange 3. This extends the full length of the post to strengthen the same and is preferably arranged midway between the side edges of the back 1 and makes the post T-shape in cross-section, as shown in Fig. 2.

40 The anchor plate 4 is secured against the front face of the back 1 by a metal clip 5. Said plate 4 extends beyond the side edges of the back 1 and is provided with two spaced holes 6, 6 on opposite sides of the back, as shown in Figs. 2 and 4. These holes 45 6, 6 clear the side edges of the back and allow the prongs 7, 7 of the clip 6 to extend therethrough to be clinched against the rear face of the back 1 over its side edges, 50 as shown in Fig. 2.

To hold the plate 4 against movement or displacement endwise of the post, the latter is provided at said plate with outwardly projecting studs 8, 8. As shown in the drawings, one of these studs 8 is just above the

upper edge of the plate and projects outward over the same. Another stud 8 is at the lower edge of said plate and projects outward over the same, while the third stud is about midway between the first two and 60 extends outward through the plate through a hole 9 therein.

These studs 8, 8 prevent the anchor plate 4 from sliding upon the post when the latter is driven in the ground. In the structure 65 shown in the drawings, the clip 5 is just below the mid-stud 8. Thus any tendency of the clip 5 to creep up on the post while driving the latter into the ground is resisted by this mid-stud. The clip 5 being located 70 in the lower part of the plate 4 holds that portion of the plate tightly against the post and resists any tendency of the lower end of the plate to be sprung outwardly away from the back 1 by dirt wedging into the 75 space between the plate and back when driving the latter in the ground.

It is preferable to make the clip 5 semi-cylindrical or half round in cross-section so that no shoulders are provided on the clip 80 to resist driving the post into the ground and moreover bear substantially flatwise against said plate 4. The holes 6, 6 for the prongs 7, 7 of the clips 5 are also given the same shape.

The rest of the post 1 may be provided with studs by making them integral with the post when rolling it and spacing them apart lengthwise of the post as shown in the drawings. These studs are indicated by 10, 90 10 and the ones above the ground form supports for the fence wires (not shown). The studs or lugs 8 and 10 extend outward from and are aligned by a low rib 11, which projects from the front face of the post flange 1 and rolled lengthwise thereof. This rib 11 is arranged along the middle of the front flange 1 of the post, and the anchor plate 4 is held against it by the clip 5. The clip 5 provides means for securing the plate 4 to 95 the post without making holes in the latter and thus avoids weakening it by holes as heretofore.

While I have shown and described herein in detail an anchor plate fastening means 105 of my invention, it is of course to be understood that the details of construction and arrangement of parts may be variously changed and modified without departing from the spirit and scope of my invention. 110

I claim as my invention:

A metallic fence post having a flat surface provided with a row of integral studs spaced at intervals lengthwise of the post, a ground anchor plate having a single aperture for accommodating one of said studs so the plate may lie flatwise against said surface, and arranged on the post with the ad-

jacent studs at the upper and lower edges of the plate and means for holding the plate 10 in contact with the post.

In testimony that I claim the foregoing as my invention, I affix my signature this 16th day of November, A. D. 1922.

RAYMOND C. KNOPKE.
